CLAIM

We claim the ornamental design for a frontload drying
appliance, as shown.

DESCRIPTION

FIG. 1 is a first top perspective view of the frontload drying
appliance of the present invention;

FIG. 2 is a second top perspective view of the frontload
drying appliance of the present invention;

FIG. 3 is a top plan view of the frontload drying appliance
of the present invention;

FIG. 4 is a bottom plan view of the frontload drying
appliance of the present invention;

FIG. 5 is a first side elevation view of the frontload drying
appliance of the present invention;

FIG. 6 is a second side elevation view of the frontload drying
appliance of the present invention;

FIG. 7 is a third side elevation view of the frontload drying
appliance of the present invention; and,

FIG. 8 is a fourth side elevation view of the frontload drying
appliance of the present invention.

The broken lines in the figures show portions of the front-
load drying appliance that forms no part of the claimed
design.
